CLAIM

The ornamental design for puncture site patch with post injection safety sealing, as shown and described.

DESCRIPTION

FIG. 1 is a lower perspective view of an embodiment of a puncture site patch with post injection safety sealing;
FIG. 2 is a rear perspective view of the puncture site patch with post injection safety sealing design of FIG. 1;
FIG. 3 is a front view of the puncture site patch with post injection safety sealing design of FIG. 1;
FIG. 4 is a rear view of the puncture site patch with post injection safety sealing design of FIG. 1;
FIG. 5 is a left side view of the puncture site patch with post injection safety sealing design of FIG. 1;
FIG. 6 is a right side view of the puncture site patch with post injection safety sealing design of FIG. 1;
FIG. 7 is a top view of the puncture site patch with post injection safety sealing design of FIG. 1; and,
FIG. 8 is a bottom view of the puncture site patch with post injection safety sealing design of FIG. 1.
